(57) **CLAIM**

The ornamental design for a dual chambered fluid dispenser, as shown and described.

DESCRIPTION

FIG. 1 is a top perspective view of an ornamental design for a dual chambered fluid dispenser with caps in a closed position;

FIG. 2 is a bottom perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom view thereof;

FIG. 9 is a top perspective view thereof, with the caps in an open position;

FIG. 10 is a bottom perspective view thereof, with the caps in the open position;

FIG. 11 is a front elevation view thereof, with the caps in the open position;

FIG. 12 is a rear elevation view thereof, with the caps in the open position;

FIG. 13 is a right side elevation view thereof, with the caps in the open position;

FIG. 14 is a left side elevation view thereof, with the caps in the open position;

FIG. 15 is a bottom view of the dual chambered fluid dispenser shown in FIG. 14, with the cap removed for a clear disclosure of the underlying portions;

FIG. 16 is a top plan view of the dual chambered fluid dispenser shown in FIG. 14, with the cap removed for a clear disclosure of the underlying portions; and,

FIG. 17 is a sectional view of the dual chambered fluid dispenser shown in FIG. 14, taken along a section line 17-17 in FIG. 16.

The broken lines in FIG. 17 are included for the purpose of illustrating the interior portions of the dual chambered fluid dispenser that form no part of the claimed design.
